UNITED STATES PATENT OFFICE.

JOSEPH F. KELLER AND WILLIAM A. WARMAN, OF NEW YORK, N. Y., ASSIGNEES TO KELLER MECHANICAL ENGRAVING COMPANY, OF NEW YORK, N. Y., A CORPORATION OF NEW YORK.

ENGRAVING-MACHINE.

1,243,182.

Specification of Letters Patent. Patented Oct. 16, 1917.

Application filed September 7, 1915. Serial No. 49,412.

To all whom it may concern:

Be it known that we, JOSEPH F. KELLER and WILLIAM A. WARMAN, both citizens of the United States, and both residents of 5 New York, in the county of New York and State of New York, have invented certain new and useful Improvements in Engraving-Machines, of which the following is a specification.

10 Our invention relates to automatic engraving machines of the type or class where- in a die or mold is produced from a model or pattern, and in which a tracer carried by a pivotally supported swinging frame 15 contacts with and follows the contour of a moving pattern, while a revolving cutter also carried by said swinging frame repro- duces the pattern in a moving block of steel or other suitable material, thus forming a 20 die or mold corresponding with the pattern; the motion of the pattern and die being of such a character that every part of the sur- face of the pattern is brought into contact with the tracer, and every feature or detail 25 of such surface is reproduced in the die; the tracer being enabled to follow the contour of the pattern because of its being supported in a swinging frame, as stated, and the pat- tern and die being carried by and secured 30 to a suitable moving table or tables, as will hereinafter more fully appear.

Such engraving machines are commonly known and referred to as pantographic machines because of the fact that the movement 35 of one element, the cutter, is controlled by the movement of another, the tracer; and our invention as the same is disclosed and claimed in this application is in the nature of an improvement in the engraving ma- 40 chine covered by our prior Patent, No. 956,769, dated May 3, 1910, for machine for engraving or sinking dies; the object of our present invention being to provide various improvements in the engraving machine to 45 which said patent relates whereby the convenience of manipulation, the range of oper- ation and of use, and the efficiency and general utility of said prior machine, are en- hanced.

50 With the above and other objects of in- vention in view, our invention consists in the improved engraving machine and subor- dinate and auxiliary features thereof illus-

trated in the accompanying drawings and hereinafter described and claimed, and in 55 such variations and modifications thereof as will be obvious to those skilled in the art to which our invention relates.

In the drawings accompanying and form- ing a part of this application and wherein 60 the preferred embodiment of our invention is illustrated:

Figure 1 is a view showing our improved engraving machine in side elevation;

Fig. 2 is a view showing an end elevation 65 of the same as seen from a position to the right of Fig. 1, certain parts being broken away to better show other parts;

Fig. 3 is a fragmentary view illustrating 70 an alternative arrangement of our engraving machine whereby a modified mode of operation is secured;

Fig. 4 is a view showing details of con- 75 struction of a clutch member employed in our machine;

Fig. 5 is a view showing a detail of mech- 80 anism whereby our machine may be manu- ally operated, the same being taken upon a horizontal plane indicated by the line 5—5, Fig. 1;

Fig. 6 is a view showing the feed mech- 85 anism for the swinging frame supporting slide enlarged, and in detail;

Fig. 7 is a view taken upon a transverse plane indicated by the line 7—7, Fig. 6, look- 85 ing toward the left;

Fig. 8 is a view showing certain details 90 of construction of a pawl or feed dog in- cluded in said feed mechanism;

Fig. 9 is a view showing details of con- 95 struction of a friction drive member for operating the feed mechanism shown in Figs. 6 and 7;

Fig. 10 is a fragmentary view in side ele- 95 vation illustrating a modified arrangement of the pattern and die supporting table and of the feed mechanism therefor, and a modified form of support for said tables;

Fig. 11 is a similar view showing the 100 same in plan;

Fig. 12 is a similar view showing an end elevation of said modified form;

Fig. 13 is a similar view illustrating a 105 capability of arrangement of certain ele- ments of our machine whereby a modified mode of operation may be secured;

Fig. 14 is a view showing a section taken upon a horizontal plane indicated by the line 14—14, Fig. 12;

Fig. 15 is a fragmentary view illustrating a portion of the swinging frame of our machine, and also certain features associated with the rotating cutter carried thereby;

Fig. 16 is a sectional view showing the driving pulleys for the rotating cutter; and

Fig. 17 is a sectional view showing the holding member for the rotary cutter by itself, with a cutter in place therein.

Referring to the drawings, the reference numeral 20 designates a suitable base or pedestal which may be of any desired form so long as it serves to support the various elements of our machine hereinafter referred to in proper positions with reference to one another. Located adjacent the upper end of the base are horizontally arranged guides 21, upon which guides a reciprocating supporting member or slide 22 moves; which slide serves as a support for a reciprocating and swinging frame 23, the connection between the slide and frame being through pivots shown at 24; from which construction it follows that said frame moves horizontally as the slide 22 moves along the guides 21, and that the free right hand end of said frame may partake of a swinging movement.

The base or frame 20 is also provided with a second pair of guides 25, these guides being transverse with reference to the guides 21, or vertically arranged, and 26 designates a vertically movable table or platen the movements of which are guided by said last mentioned guides, from which it follows that the slide 22 and table 26 move in paths transverse to one another, or at right angles to one another in the embodiment of our invention illustrated. The table 26 serves as a support for the model or pattern 27 and for the die 28 when the machine is in use, the pattern and die being secured to the table in any suitable way as by means of right angle brackets 29 having set screws which engage the pattern and die as shown.

The reciprocating and swinging frame 23 carries at its free end a tracer 30 which contacts with the pattern 27, and also a rotating cutter 31 which cuts away the material of the block in which the die 28 is formed; the tracer moving in contact with and following the irregularities of the pattern while the rotary cutter reproduces said pattern in the block in forming the die. When the machine is in operation the table 26 is moved upward, the slide 22 is then moved a short distance or step to the right or left, (means being provided for moving the slide in both directions, as will herein-after appear), to advance the cutter and tracer, and the table is then moved downward at the end of which downward move-

ment the slide is again advanced; the advance movements of the slide and, consequently, of the cutter and tracer, taking place at the ends of the upward and downward movements of the table 26 which carries the pattern and the die being formed.

The tracer 30 and cutter 31 are held in contact with the model and die by means of a weight 32 supported from one arm of a bell-crank lever 33 by means of a flexible cord or rope 34, said bell-crank lever being loose upon a shaft 35 supported in suitable bearings carried by the frame of the machine. The other arm of the lever 33 is connected with the swinging frame 23 through a flexible cord or rope 36, from which it follows that the pull of the weight 32 acts through the mechanism above described to hold the tracer and cutter in contact with the model and die, and causes the tracer to follow the irregularities of the surface of the model and the cutter to reproduce the model in the die. A spring 37 is interposed between the slide 22 and the swinging frame 23, see Figs. 1 and 2, and acts in opposition to the weight 32, thus partially neutralizing the action of the weight. This spring acts to swing the frame 23 outward and move the tracer and cutter away from the model and die when the weight 32 is lifted, as will be herein-after more fully described.

The rotating cutter 31 is carried by a rotary carrier or quill 38, see Figs. 15 and 17, which carrier rotates within a sleeve 39 clamped and held against rotation in a bifurcated arm at the free end of the frame 23 by a bolt 40, but which sleeve, rotary carrier, and cutter may be readily removed from the machine by loosening the bolt, as will be understood. The outer end of this carrier is squared, as at 41, and 42 designates a pulley which serves to drive the cutter carrier or quill and the cutter carried thereby. This pulley is supported upon a sleeve 43 supported by a bracket 44 carried by the frame 23, and the same is provided with a plate 45 having an opening corresponding in form with and through which the squared end 41 of the cutter carrier enters, and with which opening said squared end fits somewhat loosely, so as to avoid binding between the squared end and plate, as shown in Fig. 15; the pulley being thus in driving engagement with the cutter carrier and the latter being driven from the pulley, as will be understood. It will be appreciated that the construction here referred to and described permits the cutter carrier, sleeve, and cutter to be readily removed from the machine and a new cutter, or a new carrier and cutter, substituted therefor with a minimum delay or inconvenience, which is of importance as it is frequently desirable to change cutters as the work progresses and

to use cutters of different and particular forms for particular kinds of cuts to be made, or work to be done. It is further obvious that such a change may be made without disturbing the driving pulley 42, and also that the strain of the driving belt for the carrier and cutter is taken up entirely by the sleeve 43, and that the carrier is subjected to no strain by the driving belt.

10 The rotating cutter is operated by an electric motor 46 carried by the swinging frame 23 and the shaft 47 of which carries a sleeve 48 having a longitudinally extending passage 49, see Fig. 16, which sleeve carries a large pulley 50 and a small pulley 51, each having one or more grooves in its periphery to receive a round driving belt. These pulleys are both loose upon the sleeve 48, but either one of them may be locked to the sleeve so as to be driven therefrom, in which case the other pulley is free to rotate upon the sleeve; this locking being accomplished by means of a member 52 slidably in the passage 49 and operatively connected with a key 53, which key is slidable in a slot 54 provided in the sleeve and may be made to enter one of two key-ways 55, 56 provided in the pulleys, thus locking either one of the pulleys to the sleeve while permitting the other to rotate freely thereupon. The pulleys are held in place upon the sleeve by a collar 57 in threaded engagement therewith.

25 The pulleys 50, 51 drive the rotating cutter through a belt 58 passing one or more times about said pulleys, and two or more times about the pulley 42, which drives the cutter holding member or quill 38, the belt being kept tight by means of slack adjusting pulleys 59 adjustable along a support 30 60 carried by the frame 23, and about which the belt passes; from which it will be appreciated that the cutter will be driven fast from the large pulley 50, or slow from the small pulley 51, according to which of said pulleys is locked to the sleeve 48, the pulley not so locked to the sleeve running idly thereupon, as will be understood.

The vertically movable table 26 is moved up and down upon the guides 25 by means of a vertically arranged feed screw 61 supported in suitable bearings located adjacent the ends of the guides, which screw is in operative engagement with a threaded lug or nut carried by the table 26. This feed screw is driven from a vertical shaft 62 through a clutch member 63 of such a construction that the shaft and screw may be locked together so that the screw is driven through the clutch, or may be disconnected so that the screw will not be driven from the shaft, which clutch member will be described in detail hereinafter; and the shaft in question is driven by any suitable motor, such, for example, as the reversible electric motor 64 through any suitable reducing gearing

such as is shown in Figs. 1 and 2 as comprising a gear 65 upon the horizontal shaft of the motor 64, a pinion 126 operated by said gear, and spiral gears within the casing 157 intermediate said pinion and the vertical 70 shaft 62. The direction of rotation of the armature of the motor 64 is reversed by means of a suitable reversing switch such as is shown conventionally at 66; and this switch is automatically operated to reverse 75 the motor at the ends of the upward and downward movements of the table 26 by means of a vertically extending bar or rod 67, the lower end of which is operatively connected with said switch and the upper 80 end of which carries two stops 68; said stops being engaged at the ends of the upward and downward movements of the table by a lug 69 carried by the table and having a hole through which the rod extends, whereby the 85 direction of rotation of the feed screw 61, and the direction of movement of the table, will be reversed each time the table arrives at the end of its movement in either direction, as will be understood.

The stops 68 are commonly made adjustable upon the upper end of the rod 67 in order that the extent of travel of the table may be varied and adjusted, as will obviously be necessary in order to adapt the machine 95 to operate upon patterns of different sizes, and to produce dies of different sizes, this adjustment being provided for in the embodiment of our invention illustrated by providing a threaded engagement between 100 the rod and the stops; and it will be appreciated that the rod fits loose in the opening referred to in the lug 69, so that the lug may move along the rod without moving the same until one of the stops is engaged as above 105 pointed out.

The clutch member 63, see Fig. 4, comprises a sleeve 70 rigidly secured to the upper end of the shaft 62 and into which the lower end of the feed screw 61 extends, and 110 71 is a second sleeve slidably upon but in permanent driving engagement with the feed screw through a key 72 and key way 73. The meeting ends of the two sleeves are provided with teeth 74, as shown, whereby when 115 said teeth are in engagement the sleeve 71 will be driven from the sleeve 70; and a screw 75 is provided for holding the sleeve 71 in a position such that the teeth will be out of engagement when the feed screw and 120 shaft are disconnected from one another and the table is to be manually operated.

The purpose of the clutch 63, which may be of any suitable form so long as the end in view is attained, is to permit the feed screw 125 to be disconnected from the driving motor and the table 26 operated manually by means of a suitable hand wheel 76 at the outer end of a shaft 77, which shaft in turn is supported in bearings in a bracket 78 sup-

ported from the frame of the machine; said shaft being operatively connected with the feed screw 61 as through a pinion 79 upon the inner end of the shaft, an idle gear 80 with which said pinion 79 engages, and a gear 81 fast upon said screw and with which the gear 80 engages. The hand wheel is preferably loose upon the shaft 77, and is connected therewith by means of a spring-pressed pin 82 adapted to enter holes provided in a disk 83 fast upon the shaft, so that the wheel may be disengaged from the shaft and permitted to remain at rest when not in use for operating the table, as will be understood.

The horizontally movable supporting member or slide 22 is moved along the guides 21 by means of a feed screw 84 supported in bearings 85 at the ends of the guides, and which screw is in threaded engagement with a nut or lug carried by the slide and shown in dotted lines at 86, Fig. 1. This feed screw is given a step by step rotary or angular motion to automatically advance the slide at the ends of the upward and downward movements of the table 26, as above explained, and at the time that the motor 64 is reversed, by means of clutch mechanism comprising a reciprocating clutch dog or pawl 87 which grasps a clutch ring 88 carried by a disk 89 permanently secured to the screw, the pawl having a recess 90 for receiving the clutch ring and a hardened steel plate 91 having a notch which fits over the clutch ring and grasps the same, and which plate forms the immediate driving means for the clutch ring, the clutch ring being grasped between the lower wall of the notch in the plate 91 and the upper wall of the recess 90, as best shown in Figs. 6, 7 and 8.

The clutch pawl 87 is provided with a slot 92 at its upper end, and 93 is a threaded pin or screw extending through said slot and into an arm 94 projecting from an oscillating collar or ring 95 supported concentrically with reference to the feed screw 84 as upon a sleeve 96 extending from the bearing 85, whereby the pawl is capable of a slight oscillatory and up and down movement with reference to the screw 93 in order that the walls of the recess 90 and notch in the steel plate 91 may properly adapt themselves to and grasp the clutch ring 88.

The clutch mechanism above referred to is designed and adapted to rotate the feed screw 84 in both directions to thereby move the slide 22 and swinging frame 23 either to the right or left, this being accomplished by providing two screws 97, 98, both in threaded engagement with the arm 94, and each of which screws is provided with an abutment 99, each abutment being kept from turning as the screws are rotated in any way as by a pin entering a hole in the arm 94 as shown in dotted lines, Fig. 8. The clutch

pawl 87 is provided with two oppositely located recesses 100, one of which is shown in Fig. 8, and springs 101 are located in these recesses, the outer ends of which springs bear against the abutments 99.

Referring now to Fig. 7, if the screw 97 be loosened and the screw 98 be screwed in so that the abutment 99 carried by it rests against the side of the arm 94, as shown, then the spring 101 which acts against the abutment carried by said screw 98 will swing the pawl 87 to the left, and, upon a downward movement of the link 102, the pawl will be moved to the right, during which movement the clutch ring 88 will be grasped in the manner illustrated and the feed screw 84 advanced a step in a clock-wise direction, the feeding taking place upon a downward movement of the link 102; while the pawl will slip along the clutch ring without grasping it as the pawl is moved to the left and returned to its initial position during an upward movement of the link 102.

If now the screw 98 be loosened, and the screw 97 screwed in so that its abutment 99 rests against the side of the arm 94, then the spring 100 which acts against the abutment carried by said screw 97 will swing the pawl 87 to the right, and, upon an upward movement of the link 102 the pawl will be moved to the left, during which movement the clutch ring will be grasped by the pawl and the feed screw advanced a step in a counter clock-wise direction, the feeding here taking place upon an upward movement of the link 102; while the pawl will slip along the clutch ring without grasping it as said pawl is moved to the right and returned to its initial position during a downward movement of the link 102.

Finally, if both the screws 97, 98 be screwed inward the abutments 99 carried by the screws will act as stops to limit sidewise movement of the pawl in both directions, and said pawl will be held in a central or neutral position, under which condition of the parts in question the clutch ring 88 will not be grasped during either the upward or the downward movement of the link 102. The feed screw 84 will not be operated at all when the parts are in such a position, and the feed mechanism for the feed screw in question will be entirely disconnected from the means hereinafter referred to and described whereby it is operated automatically in the normal operation of the machine.

The upper end of the link 102 is pivotally connected with a second arm 103 carried by and extending from the oscillating collar 95, and through which arm the feed mechanism is operated, as will be understood, and the lower end of said link is pivotally connected with an arm 104 of a friction disk 105; said disk being loose upon a shaft 106

driven from the vertical shaft 62, see Fig. 1, through bevel gears 107; from which it will be obvious that the direction of rotation of said shaft 106 is reversed each time the motor 64 is reversed. The shaft 106 carries two disks 108 located one upon either side of the friction disk 105, and 109 are two disks or washers of leather or similar material held by a yielding force between the disks 108 and the friction disk 105, as best illustrated in Fig. 1. The arm 103 is provided with an abutment 110, and 111 is an adjustable stop in the form of a screw in threaded engagement with a fixed lug 112, and with which stop said abutment engages as the arm 103 swings downward, as shown in the dotted lines Fig. 7, to thereby determine the angular movement of the feed screw and regulate the feed.

It will therefore be appreciated that as the shaft 106 rotates in a counter-clockwise direction, referring to Fig. 9, the friction disk 105 will be carried in the same direction, motion being transmitted to the friction disk through the leather disks, and its arm 104 will move the link 102 bodily upward and swing the arms 103 and 94 and the clutch pawl into about the positions shown in full lines, Fig. 7, this figure showing the positions assumed by the parts as the arm 104 arrives at a vertical position. As the arm 104 moves from its vertical position toward the position shown in dotted lines, Fig. 9, the link 102 moves downward, whereupon the clutch pawl 87 grasps the clutch ring 88 and imparts a limited angular movement to the feed screw 84, thus advancing the slide 22 a step as hereinbefore explained. The friction disk 105 moves with the shaft 106 and the link 102 moves downward until the abutment 110 engages the stop 111, after which slipping occurs between the leather disks and the friction disk and no further motion is transmitted to the latter so long as the shaft 106 continues to rotate in the direction above assumed. When, however, the direction of rotation of the shaft 106 is reversed, and rotation in a clock-wise direction commences, the friction disk will be moved in a corresponding direction and the arm 104 will be moved from the dotted line into the full line position shown in Fig. 9, which movement will be accompanied by an upward movement of the link 102 and by an angular movement of the feed screw 84, such movement and the step by step advance movements of the slide 22 taking place at each reversal of the motor 64, and as the shaft 106 begins to rotate in a new or reversed direction.

Secured to the free inner end of the feed screw 84 is a graduated wheel 113 having a spring pressed locking plunger 114 slideable in a recess formed in the hub thereof

and which plunger may enter a hole provided in a sprocket wheel 115 carried by and rotatable upon the hub of said graduated wheel, as shown in Fig. 6, to thereby lock said graduated wheel and sprocket together, or, upon said locking plunger being withdrawn from the hole and held out of the same, to disconnect the sprocket wheel from the graduated wheel. Said sprocket wheel is driven from a hand wheel 116 supported at the outer end of a shaft 117, which shaft is supported upon a bracket 118 extending from the frame of the machine; the inner end of said shaft carrying a gear 119 which drives a second gear 120 and a second sprocket wheel 121; the sprocket wheels 115 and 121 being connected by a sprocket chain 122, see Figs. 1, 2 and 5.

From the above it will be appreciated that when the plunger 114 is in a position to lock the sprocket wheel 115 and the graduated wheel 113 together, the feed screw 84 may be operated manually by the hand wheel 116 and the slide 22 and frame 23 moved in either direction, the feed dog or pawl 87 being placed in its middle or neutral position at such times and held therein as above explained, in order that it may not interfere with the rotation of the clutch ring 88 when the feed screw is being operated by or from the hand wheel.

A pointer 123 is preferably provided, the free end of which lies adjacent the periphery of the graduated disk and whereby the rate of feed may be observed and determined, the extent of each angular movement of the graduated disk and feed screw being determined by adjusting the screw or adjustable stop 111, as will be understood.

It was above explained how the machine could be arranged so that the pattern and work or die supporting table 26 could be manually operated by the hand wheel 76, and it has just been shown that the swinging frame 23 and tracer and rotary cutter carried thereby may be manually operated by the hand wheel 116, these two capabilities of operation being independent of one another as will be appreciated. This capability of manual operation is of great advantage in engraving machines of the type to which our invention belongs, as the operator is thereby enabled to perform a variety of milling, profiling, and similar operations, to take heavy cuts upon portions of the work as opportunities for such cuts may occur, to rough out work preparatory to taking finishing cuts with the machine operating automatically, and in general to extend the range of the work which may be done upon the machine and to expedite the work being done at such times and under such conditions as the judgment of the operator may dictate.

It is frequently desirable when the machine is being controlled manually by means of the hand-wheels 76 and 116 as above explained to move the cutter 31 and, as necessarily follows, the tracer 30 away from the pattern and die and, in the machine illustrated, means are provided whereby the motor 64, which is left running in the proper direction, may accomplish the end above referred to by lifting the weight 32 and permitting the spring 37 to swing the swinging frame 23 away from the model and the die, thus removing the tracer and cutter therefrom, it being above explained that the spring 37 acts in opposition to the weight 32.

The mechanism shown whereby the motor may be made to lift the weight 32 is as follows: The reference numeral 124 designates a drum loose upon the shaft of the motor 64, see Fig. 2, and 125 designates a gear driven by the motor shaft through the gear 65 in the direction indicated by the arrow. Secured to the shaft which supports the gear 125 is a friction pulley 127, and 128 designates a belt extending about the friction pulley 127 and over the drum 124, see Fig. 1, and the lower end of which belt is connected with a treadle 129. The other end 30 of the belt 128 is connected with a cord or rope 130, the other end of which cord is in turn connected with an arm 131 operatively secured to the shaft 35 hereinbefore referred to. The shaft 35 also carries a second arm 35 132 the free end of which is connected with the weight 32 through a cord 133, see Figs. 1 and 2. This cord 133 is normally somewhat slack, as shown in Fig. 2, so that the normal up and down movements of the weight 32, as the frame 23 swings in and out, will not be interfered with; said cord being drawn taut and acting to lift the weight only when the tracer and cutter are to be moved away from the pattern and die.

45 The friction between the pulley 127 and the belt or strap 128 is normally insufficient to cause said pulley to grasp the strap and lift the weight 32 through the connections above referred to. When, however, the 50 treadle 129 is depressed by the foot of the operator the belt will be drawn into contact with the pulley 127, and, said pulley being continuously driven in the proper direction by the reversible motor 64 as will be understood, the belt will be grasped and a pull will be exerted through the cord 130 which will oscillate the shaft 35 and lift the weight 32 through the cord 133, thus permitting the spring 37 to swing the oscillating arm 60 outward and move the tracer and cutter away from the model and die. The reversing stops 68 are moved out of the way when the machine is being operated manually and when the mechanism last above described is

being used, so that the motor will not be 65 reversed, but will run continuously in a direction to exert a pull upon the strap when the treadle is depressed.

The swinging frame 23 is counterbalanced so that the pivots 24 whereby it is supported and held in proper position are relieved 70 from the weight of the frame by mechanism comprising a cord 134, the lower end of which is connected with said frame and the upper end of which is connected with one 75 arm of a lever 135, and a weight 136 suspended from the other end of said lever by a cord 137. The vertically moving table 26 is also preferably counterbalanced by means of a weight 138 suspended from a lever 139, 80 which lever is connected with said table by a cord 140, all as shown in Fig. 2 of the drawing.

While the table 26 has been thus far referred to as in effect a single structure and 85 is so illustrated in Figs. 1 and 2, it is commonly made in two parts which may be either secured together to thereby form a single or unitary structure, or disconnected from one another. When the parts of the 90 table are secured together, as in Figs. 1, 2 and 13, they form in effect and move as a single structure, and the machine when in operation will reproduce the pattern in forming a die, or will duplicate an existing 95 die if such a die be used as a pattern, in the manner hereinbefore explained and as illustrated in Figs. 1 and 2. If, however, the two parts of the table be disconnected from one another and said parts be made to move 100 simultaneously toward and from one another, as by means of the table feed mechanism illustrated in Figs. 10 to 12, which feed mechanism is equally and in the same way 105 applicable to and capable of use with the form of our machine shown in Figs. 1 and 2, then and in such a case when the machine is in operation the pattern and die will be reversed with reference to one another, as 110 illustrated in Fig. 3, or will be right and left as is necessary in the case of two-part dies used in pairs; from which it follows that a right die may be produced from a left pattern, or left die used as a pattern, and vice versa.

Figs. 10 to 14 illustrate a modified form of our invention so far as concerns the manner of supporting the table which carries the pattern and die; and illustrate also an attachment or auxiliary device for use with the table feed screw, which attachment is capable of use also with the form of our machine shown in Figs. 1 and 2, by the use of which the two parts of the table are made 120 to move simultaneously toward and from one another for the purpose above stated.

In these figures the frame of the machine is provided with a curved seat 141 extending

transverse to the path of travel of the supporting slide 22 and the center or axis of which seat, or the axis of curvature thereof, coincides with the axis of the feed screw 142 which corresponds in all respects with the feed screw 61 hereinbefore referred to. Secured in place upon the curved seat 141 is a table support 143 which is angularly adjustable about a vertically extending axis 10 corresponding with the axis of the feed screw 142, the support being held in place in any position it may be adjusted into by means of screws 144 extending through slots 145, and the inner ends of which screws are in threaded engagement with the rear wall of the table support, as shown in Fig. 14.

The table support is provided with guides 146, and 147 designates the two parts of the table upon which the pattern and die 20 are supported. These parts are provided with lugs 148 at their inner ends whereby they may be secured together by means of bolts 149, as shown in Fig. 13 and as is the case in the form of our machine shown 25 in Figs. 1 and 2. The upper of the parts in question is provided with a nut 150 with which the feed screw 142 is in threaded engagement and whereby the combined table is moved when the two parts thereof are secured 30 together as in Figs. 1, 2 and 13, and whereby the upper only of said two parts is moved when said parts are not secured together.

The means for causing the lower of the 35 two parts 147 which together form the table to move in a direction opposite from the direction of movement of the upper part comprises an auxiliary feed screw 151 secured to the upper end of the main feed 40 screw 142, one of said screws having a right and the other a left hand thread. The auxiliary screw 151 is in threaded engagement with a nut 152, which nut is operatively connected with the lower of the two 45 parts of the supporting table through rods 153, the upper ends of which rods are connected with said nut and the lower ends with lugs 154 at the upper end of said lower part, as illustrated.

50 The feed screw 142 is capable of being operated by a hand wheel 76, this hand wheel and the means whereby the feed screw is operated thereby being the same as has hereinbefore been described at length in describing 55 the form of our invention illustrated in Figs. 1 and 2. The reversing bar or rod 155 is also substantially the same in construction, and operates in the same way and through the same mechanism to reverse the direction 60 of rotation of the feed screw 142 as the reversing bar hereinbefore described at length. The operating lug 156 for the bar, however, differs somewhat from the lug 69 in that it is provided with a segmental slot, as shown 65 in Fig. 11, in order that the table support

and table may be tilted into an inclined position, as illustrated in dotted lines in said figure.

It will be appreciated that upon loosening the screws 144 the table support may be moved upon the curved seat 141 and the table 147 tilted with reference to the tracer and cutter, as shown in dotted lines, Fig. 11, without in any way interfering with the feed mechanism which operates the table. 75 This is a feature of importance in the practical operation of the machine, as it permits the pattern and die to be so adjusted and positioned relative to the tracer and cutter as to secure maximum convenience 80 and efficiency in the operation of the machines; that is, permits an adjustment of the parts referred to such that a particular portion of the surface of the pattern which might otherwise be inconvenient to get at 85 will be the better followed by the tracer than might be the case if the surface of the table was at or substantially at right angles to the axes of the tracer and cutter, and permits an adjustment such that the cutter will 90 operate to the best advantage as it cuts away the material of the die block, in the act of copying and reproducing the portion of the surface in question in the die. It will also be seen that upon removing the auxiliary feed screw 151 and nut 152, and securing 95 the two parts of the table together as above explained and as shown in Fig. 18, the table becomes in effect a unitary structure, and is moved up and down by the 100 main feed screw 142, the same as in the form of our machine illustrated in Figs. 1 and 2, the rods 153 being left in place, as shown in Fig. 13, if desired.

Having thus described and explained our 105 invention, we claim and desire to secure by Letters Patent:

1. In an engraving machine of the class described, a suitable supporting frame; a slide and a table supported by said frame 110 and movable transverse to one another; a swinging frame carried by said slide; a tracer and a cutter carried by said frame and adapted to engage a pattern and a die carried by said table; a feed screw for operating said slide; a sprocket wheel operatively connected with said feed screw; a second sprocket wheel; a manually operable member operatively connected with said second sprocket wheel; a sprocket chain connecting said two sprocket wheels; a second feed screw for operating said table; a manually operable member operatively connected with said table operating feed screw; a 120 motor; and driving mechanism whereby said feed screws may be operated by said motor, said driving mechanism including two clutches whereby said screws may be independently connected with or disconnected from said motor. 125 130

2. In an engraving machine of the class described, a suitable supporting frame; a slide and a table supported by said frame and movable at right angles to one another; a swinging frame carried by said slide; a tracer and a cutter carried by said frame and adapted to engage a pattern and a die carried by said table; a feed screw operatively connected with said slide; a sprocket wheel carried by said feed screw; means for locking said sprocket wheel and screw together so that the screw may be driven by the wheel; a second sprocket wheel; a hand wheel; means whereby said second sprocket wheel may be operated by said hand wheel; a sprocket chain connecting said sprocket wheels; a second feed screw operatively connected with said table; a second hand wheel; means whereby said second feed screw may be operated by said second hand wheel; a motor; and driving mechanism through which said feed screws are operated by said motor, said mechanism including two clutches whereby each of said feed screws may be connected with or disconnected from said motor.

3. In an engraving machine of the class described, a suitable supporting frame; a slide and a table supported by said frame and movable at right angles to one another; a swinging frame carried by said slide; a tracer and a cutter carried by said frame and adapted to engage a pattern and a die carried by said table; a feed screw operatively connected with said slide; a sprocket wheel carried by said feed screw; means for locking said sprocket wheel and screw together so that the screw may be driven by the wheel; a second sprocket wheel; a hand wheel; gearing intermediate said second sprocket wheel and said hand wheel, whereby said second sprocket wheel may be operated by said hand wheel; a sprocket chain connecting said sprocket wheels; a second feed screw operatively connected with said table; a second hand wheel; means whereby said second feed screw may be operated by said second hand wheel; a motor operatively connected with said second feed screw through a clutch whereby said motor may be disconnected from said screw; and means operated by said motor for intermittently operating said first mentioned feed screw.

4. In an engraving machine of the class described, a suitable supporting frame; guides carried by said frame; a slide movable along said guides; means for moving said slide; a swinging frame carried by said slide; a tracer and a cutter carried by said frame and adapted to engage a pattern and a die; other guides arranged transversely to said first mentioned guides; a table made up of two parts movable along said last mentioned guides and which parts are adapted to support the pattern and the die afore-

said; and means for moving the two parts of said table simultaneously toward and from one another.

5. In an engraving machine of the class described, a suitable supporting frame; guides carried by said frame; a slide movable along said guides; a feed screw operatively connected with said slide; a swinging frame carried by said slide; a tracer and a cutter carried by said frame and adapted to engage a pattern and a die; other guides arranged at right angles to said first mentioned guides; a table made up of two parts movable along said last mentioned guides and which parts are adapted to support the pattern and the die aforesaid; a motor; means operated by said motor for imparting intermittent angular movement to said feed screw; and means operated by said motor for moving the two parts of said table simultaneously toward and from one another.

6. In an engraving machine of the class described, a suitable supporting frame; guides carried by said frame; a slide movable along said guides; a feed screw operatively connected with said slide; a swinging frame carried by said slide; a tracer and a cutter carried by said frame and adapted to engage a pattern and a die; other guides arranged at right angles to said first mentioned guides; a table made up of two parts movable along said last mentioned guides and which parts are adapted to support the pattern and the die aforesaid, said parts being movable simultaneously toward and from one another; a reversible motor; means operated by said motor for imparting intermittent angular movement to said feed screw; means operated by said motor for moving the two parts of said table alternately toward and from one another; and means operated by one of the parts of said table for reversing said motor.

7. In an engraving machine of the class described, a reciprocating and swinging frame; means for imparting reciprocating motion to said frame; a reciprocating table movable in a direction transverse to the direction of reciprocating movement of said frame, and which table is made up of two parts; means for moving the two parts of said table simultaneously toward and from one another; and a tracer and a cutter carried by said frame and adapted to engage a pattern and a die supported one upon each of the parts of said table.

8. In an engraving machine of the class described, a reciprocating supporting member; means for imparting reciprocating motion to said supporting member; a swinging frame carried by said reciprocating member; a tracer and a cutter carried by said frame and adapted to engage a pattern and a die; guides arranged transverse to the path of travel of said reciprocating mem-

r; a table made up of two parts movable along said guides and which parts are adapted to support the pattern and the die aforesaid; and means for moving the two parts of said table simultaneously toward and from one another.

9. In an engraving machine of the class described, a reciprocating supporting member; a feed screw operatively connected with said member and adapted to impart reciprocating motion thereto; a swinging frame carried by said reciprocating member; a tracer and a cutter carried by said frame and adapted to engage a pattern and a die; guides arranged transverse to the path of travel of said reciprocating member; a table made up of two parts movable along said guides and which parts are adapted to support the pattern and the die aforesaid; a second feed screw operatively connected with one of the parts of said table; means operated by said second mentioned feed screw for operating the other of the parts of said table; and means for operating said feed screws.

10. In an engraving machine of the class described, a reciprocating supporting member; means for operating said member; a swinging frame carried by said reciprocating member; a tracer and a cutter carried by said frame and adapted to engage a pattern and a die; guides arranged transverse to the line of travel of said reciprocating member; a table made up of two parts movable along said guides and which parts are adapted to support the pattern and the die aforesaid; a feed screw in operative engagement with one of the parts of said table; a nut operatively connected with the other of said parts; an auxiliary feed screw operated by said first mentioned feed screw and in threaded engagement with said nut; and means for operating said first mentioned feed screw.

11. In an engraving machine of the class described, a reciprocating supporting member; means for operating said member; a swinging frame carried by said reciprocating member; a tracer and a cutter carried by said frame and adapted to engage a pattern and a die; guides arranged transverse to the path of movement of said reciprocating member; a table made up of two parts movable along said guides and which parts are adapted to support the pattern and the die aforesaid; a feed screw in operative engagement with one of the parts of said table; a nut operatively connected with the other of said parts; an auxiliary feed screw carried by said first mentioned feed screw and in threaded engagement with said nut, said feed and auxiliary screws being threaded oppositely; and means for operating said first mentioned feed screw.

12. In an engraving machine of the class

described, a reciprocating supporting member; means for operating said member; a swinging frame carried by said reciprocating member; a tracer and a cutter carried by said frame and adapted to engage a pattern and a die; a reciprocating table movable in a path transverse to the path of movement of said reciprocating member and adapted to support the pattern and die aforesaid; means for operating said table; and means for tilting said table with reference to said tracer and cutter.

13. In an engraving machine of the class described, a reciprocating supporting member; means for operating said member; a swinging frame carried by said reciprocating member; a tracer and a cutter carried by said frame and adapted to engage a pattern and a die; an adjustable table support arranged transverse to the path of movement of said frame supporting member; a reciprocating table carried by said table support and adapted to support the pattern and die aforesaid; and means for operating said table.

14. In an engraving machine of the class described, a reciprocating supporting member; means for operating said member; a swinging frame carried by said reciprocating member; a tracer and a cutter carried by said frame and adapted to engage a pattern and a die; an adjustable table support arranged transverse to the path of movement of said frame supporting member; a reciprocating table carried by said table support and adapted to support the pattern and die aforesaid; and means for operating said table.

15. In an engraving machine of the class described, a suitable supporting frame; guides carried by said frame; a slide movable along said guides; means for moving said slide; a swinging frame carried by said slide; a tracer and a cutter carried by said frame and adapted to engage a pattern and a die; a curved seat formed upon said supporting frame and the axis of curvature of which seat extends transverse to the path of movement of said slide; a table support having a curved surface adapted to contact with said curved seat; means whereby said table support may be adjusted upon said seat; a reciprocating table carried by said table support and adapted to support the pattern and die aforesaid; and means for operating said table.

16. In an engraving machine of the class described, a suitable supporting frame; guides carried by said frame; a slide movable along said guides; means for moving said slide; a swinging frame carried by said slide; a tracer and a cutter carried by said

frame and adapted to engage a pattern and a die; a curved seat formed upon said supporting frame and the axis of curvature of which seat extends transverse to the path of movement of said slide; a table support having a curved surface adapted to contact with said curved seat; means for securing said table support in place upon said seat; guides carried by said table support; a reciprocating table movable along said guides and adapted to support the pattern and die aforesaid; a feed screw also carried by said table support and operatively connected with said table; and means for operating said feed screw.

17. In an engraving machine of the class described, a suitable supporting frame; guides carried by said frame; a slide movable along said guides; a feed screw operatively connected with said slide; a swinging frame carried by said slide; a tracer and a cutter carried by said frame and adapted to engage a pattern and a die; a curved seat formed upon said supporting frame and the axis of curvature of which seat extends transverse to the path of movement of said slide; a table support having a curved surface adapted to contact with said curved seat; means for securing said table support in place upon said seat; guides carried by said table support; a reciprocating table movable along said guides and adapted to support the pattern and die aforesaid; a feed screw also carried by said table support and operatively connected with said table; a motor operatively connected with both said feed screws; means whereby said motor may be disconnected from said feed screws; and two manually operable devices one operatively connected with each of said feed screws and by means of which said slide and table may be operated independently of one another.

18. In an engraving machine of the class described, a reciprocating supporting member; a feed screw adapted to operate said member; a swinging frame carried by said reciprocating member; a tracer and a cutter carried by said frame and adapted to engage a pattern and a die; a table support adjustable about an axis extending transverse to the path of travel of said supporting member; guides carried by said table support; a reciprocating table movable along said guides and adapted to support the pattern and die aforesaid; a feed screw adapted to operate said table; and means for operating said feed screws.

19. In an engraving machine of the class described, a reciprocating supporting member; a frame adapted to support a tracer and a cutter; two pivots adapted to support said frame from said supporting member, said frame being capable of swinging movement about a vertical axis; a counterbalancing

weight; and a flexible member between said weight and frame whereby said weight exerts a lifting action along the axis about which said frame swings, and said pivots are relieved of the weight of said frame. 70

20. In an engraving machine of the class described, a suitable supporting frame; horizontally extending guides carried by said frame; a slide adapted to move along said guides; a frame carried by said slide and adapted to support a tracer and a cutter, and which frame is capable of a swinging movement about a vertical axis; two pivots whereby said frame is supported; a counterbalancing weight; and a flexible member connecting said weight and swinging frame and through which said weight exerts a lifting action along the axis about which said frame swings, whereby said pivots are relieved of the weight of said frame. 80

21. In an engraving machine of the class described, a suitable supporting frame; guides carried by said frame; a slide movable along said guides; a feed screw operatively connected with said slide; a swinging frame; two vertically arranged pivots whereby said swinging frame is supported from said slide so as to swing about a vertical axis; counterbalancing means acting in a vertical direction and along the axis 95 about which said frame swings, whereby said pivots are relieved from the weight of said frame; a tracer and a cutter carried by said frame and adapted to engage a pattern and a die; other guides arranged transverse 100 to said first mentioned guides; a table made up of two parts movable along said last mentioned guides, and which parts are adapted to support the pattern and the die aforesaid; and means for moving the two 105 parts of said table simultaneously toward and from one another.

22. In an engraving machine of the class described, a suitable supporting frame; guides carried by said frame; a slide movable along said guides; a feed screw operatively connected with said slide; a swinging frame; two vertically arranged pivots whereby said frame is supported from said slide so as to swing about a vertical axis; counterbalancing means acting in a vertical 110 direction and along the axis about which said frame swings, whereby said pivots are relieved from the weight of said frame; a tracer and a cutter carried by said frame 115 and adapted to engage a pattern and die; a table support adjustable about an axis extending transverse to the path of movement of said slide; guides carried by said table support; a table movable along said last 120 mentioned guides and adapted to support the pattern and die aforesaid; a feed screw adapted to operate said table; and means for operating said feed screws. 125

23. In an engraving machine of the class 130

scribed, a swinging frame; a removable sleeve carried by said frame; a rotary cutter carrier carried by said sleeve and adapted to support a cutter; a driving pulley carried by said frame and located adjacent said sleeve, which pulley is supported independently of said sleeve and cutter carrier and is operatively connected with said rotary cutter carrier; and means for driving said pulley.

24. In an engraving machine of the class described, a swinging frame; a removable sleeve carried by said frame; a rotary cutter carrier carried by said sleeve and adapted to support a cutter; a driving pulley rotatable about an axis corresponding with the axis of rotation of said cutter carrier; means for supporting said pulley from said frame and independently of said sleeve and cutter carrier; and driving means intermediate said pulley and cutter carrier and through which said cutter carrier may be driven from said pulley.

25. In an engraving machine of the class described, a swinging frame; a removable sleeve carried by said frame; a rotary cutter carrier carried by said sleeve and adapted to support a cutter; a driving pulley rotatable about an axis corresponding with the axis of rotation of said cutter carrier and which pulley is in driving engagement with said carrier; and a bracket carried by said swinging frame and whereby said driving pulley is supported independently of said sleeve and cutter carrier.

26. In an engraving machine of the class described, a suitable supporting frame; guides carried by said frame; a slide movable along said guides; a feed screw operatively connected with said slide; a swinging frame carried by said slide; a tracer and a cutter carried by said swinging frame and adapted to engage a pattern and a die; other guides arranged transverse to said first mentioned guides; a table movable along said last mentioned guides and adapted to support the pattern and die aforesaid; a second feed screw operatively connected with said table; means for operating said feed screws; two manually operable feed devices one associated with each of said feed screws; and means controlled by the operator of the machine and operated by the operating means for said feed screws for effecting a swinging movement of said swinging frame in such a way as to move said tracer and cutter away from the pattern and die.

27. In an engraving machine of the class described, a suitable supporting frame; guides carried by said frame; a slide movable along said guides; a feed screw operatively connected with said slide; a swinging frame carried by said slide; a tracer and a cutter carried by said swinging frame and adapted to engage a pattern and a die;

other guides arranged transverse to said first mentioned guides; a table movable along said last mentioned guides and adapted to support the pattern and die aforesaid; a second feed screw adapted to operate said table; a friction pulley; means for rotating said pulley; a strap extending about said pulley; means for applying tension to said strap to thereby increase the friction between said strap and pulley; and means operated by said strap for effecting a swinging movement of said swinging frame in a direction to move said tracer and cutter away from the pattern and die.

28. In an engraving machine of the class described, a suitable supporting frame; a slide and a table supported by said frame and movable in directions transverse to one another; a swinging frame carried by said slide; a tracer and a cutter carried by said swinging frame; a weight operatively connected with said swinging frame and adapted to hold said tracer and cutter in contact with said pattern and die; a spring tending to swing said frame in a direction to move said tracer and cutter away from said pattern and die; two feed screws one operatively connected with said slide and the other with said table; two manually operable feed devices one associated with each of said screws and by means of which said screws may be independently operated; a friction pulley; means for rotating said pulley; a strap extending about said pulley; means for applying tension to said strap to thereby increase the friction between said strap and pulley; and means operated by said strap for lifting the weight aforesaid to thereby permit said spring to act upon said swinging frame.

29. In an engraving machine of the class described, a suitable supporting frame; a slide and a table supported by said frame and movable in directions transverse to one another; a swinging frame carried by said slide; a tracer and a cutter carried by said swinging frame and adapted to engage a pattern and a die carried by said table; means for moving said slide and table manually and independently of one another; means acting upon said swinging frame to press said tracer and cutter into contact with said pattern and die; and means controlled by the operator of the machine for moving said swinging frame in a direction to move said tracer and cutter away from the pattern and die.

30. In an engraving machine of the class described, a suitable supporting frame; guides carried by said frame; a slide movable along said guides; a feed screw operatively connected with said slide; a swinging frame; a tracer and a cutter carried by said frame and adapted to engage a pattern and a die; other guides arranged transverse to

said first mentioned guides; a table movable along said last mentioned guides and adapted to support the pattern and die aforesaid; a second feed screw operatively connected with said table; a motor for operating said feed screws; means whereby said motor may be disconnected from said feed screws; means for operating said feed screws manually and independently of one another; a weight operatively connected with said swinging frame and adapted to hold said tracer and cutter in contact with said pattern and die; a spring acting upon said frame and tending to move said tracer and cutter away from said pattern and die;

a rock shaft supported from the frame of the machine; a friction pulley driven by the motor aforesaid; a drum loosely supported upon the shaft of said motor; a treadle; a strap with which said treadle is connected and which strap extends over said drum and about said friction pulley; means whereby said strap is operatively connected with said rock shaft; and means operated by said rock shaft for lifting said weight.
